UNITED STATES PATENT OFFICE

148,011

DESIGN FOR A COMBINED HANDLE, LICENSE PLATE HOLDER, AND LAMP HOUSING

Virgil M. Exner and Vincent E. Gardner, South Bend, Ind., assignors to The Studebaker Corporation, South Bend, Ind., a corporation of Delaware

Application July 26, 1946, Serial No. 131,976

Term of patent 7 years

(Cl. D14—6)

To all whom it may concern:

Be it known that we, Virgil M. Exner and Vincent E. Gardner, citizens of the United States, residing at South Bend, in the county of St. Joseph and State of Indiana, have invented a new, original, and ornamental Design for a Combined Handle, License Plate Holder, and Lamp Housing, of which the following is a specification, reference being had to the accompanying drawing, forming a part thereof.

In the drawing:

Figure 1 is a perspective view, looking downwardly upon a combined handle, license plate holder, and lamp housing for attachment to the deck lid of a trunk compartment of an automobile vehicle showing our new design;

Figure 2 is a perspective view similar to Figure 1, but showing a pivoted handle lever of the handle in another position; and

We claim:

The ornamental design for a combined handle, license plate holder, and lamp housing, substantially as shown.

VIRGIL M. EXNER.
VINCENT E. GARDNER.
